UNITED STATES PATENT OFFICE

PETER BRANKOWITZ, OF CYPRESS HILLS, NEW YORK

DESIGN FOR A SUPPORTING BRACKET

Application filed October 1, 1931. Serial No. 41,287. Term of patent 7 years.

To all whom it may concern:

Be it known that I, PETER BRANKOWITZ, a citizen of the United States, residing at Cypress Hills, in the county of Kings and State of New York, have invented a new, original, and ornamental Design for a Supporting Bracket, of which the following is a specification, reference being had to the accompanying drawing, forming part thereof.

The figure is a perspective view of a supporting bracket, showing my new design.

I claim:

The ornamental design for a supporting bracket, as shown.

PETER BRANKOWITZ.
